UNITED STATES PATENT OFFICE.

HIRAM A. FOSS, OF ALBION, MAINE.

LIGHT-PROJECTING ATTACHMENT FOR FIREARMS.

No. 924,445.

Specification of Letters Patent.

Patented June 8, 1909.

Application filed February 11, 1909. Serial No. 477,404.

To all whom it may concern:

Be it known that I, HIRAM A. FOSS, a citizen of the United States, residing at Albion, in the county of Kennebec and State of Maine, have invented new and useful Improvements in Light-Projecting Attachments for Firearms, of which the following is a specification.

This invention relates to an attachment for firearms, whereby the latter can be used for accurate shooting by night, there being a ray of light directed on the object aimed at.

The invention has for one of its objects to improve and simplify the construction of devices of this character so as to be comparatively simple and inexpensive to manufacture, reliable and efficient in use, and so designed as to be readily applied to a firearm or removed therefrom.

Another object of the invention is the provision of a light-projecting device consisting of a tube of telescopically arranged sections and novel means for attaching the ends of the tube, when extended, to the barrel of the firearm.

With these objects in view and others, as will appear as the description proceeds, the invention comprises the various novel features of construction and arrangement of parts which will be more fully described hereinafter and set forth with particularity in the claims appended hereto.

In the accompanying drawing, which illustrates one embodiment of the invention, Figure 1 is a side view of the device applied to a rifle. Fig. 2 is a central longitudinal section of the device with an intermediate portion of the tube broken away. Fig. 3 is a perspective view of the rear attaching means for the tube. Fig. 4 is a perspective view of the front attaching means. Fig. 5 is a perspective view of the light retainer.

Similar reference characters are employed to designate corresponding parts throughout the views.

Referring to the drawing, A designates a rifle or other firearm to which is applied the light-projecting device B whereby the rifle can be used by night, the said attachment serving to direct a ray of light upon the object to be fired upon. The device B comprises a sheet metal tube of light sheet metal or other suitable material of tapering form from the rear to the front, and for convenience in storing the device when not in use on the gun, the tube is preferably made in sec-

tions a which telescope one within another. In the front end of the tube is a plug 2 having a light-emitting opening 3. In the rear larger end of the tube is a suitable light such as an incandescent lamp 4 connected with a battery 5 removably mounted in the tube and held therein by a retainer 6 hingedly connected with the rear end of the tube to extend across the outer end of the battery. When the device is used, the tube is extended by pulling out the successive sections to the position shown in Fig. 1, and the ends of the tube are attached to the barrel of the rifle.

The front end of the tube is attached to the rifle barrel by the attaching means shown in Fig. 4, which means consists of a band or ring 7 embracing the front section of the tube and suitably secured to the front sight 8 on the rifle barrel. The rifle sight comprises a dove-tail base 9 formed with a stud 10 rising therefrom which has an open sight notch 11 in its top and a transverse aperture 12. The ring 7 is formed with spaced ears 13 for engaging opposite sides of the stud 10 and a bolt or fastening screw 14 passes through the apertures 12 and 15 of the stud and ring, respectively. The screw 14 constitutes a pivot for permitting the rear end of the tube to be raised or lowered to adapt the device for different ranges. When the light projecting device is not in use, the fastening ring 7 can be thrown down against the barrel of the rifle to be out of the way, and the sight 11 can be used in the usual manner. The base 9 of the front sight is set into a dove-tail transverse slot 16 in the rifle barrel, as shown in Fig. 1.

The means for attaching the rear end of the tube to the rifle barrel consists of a spring 17 attached to a dove-tail base piece which is held in a correspondingly-shaped transverse groove 19 in the rifle barrel at the rear end thereof. On the free end of the spring is a hingedly-connected pawl 20 which is adapted to engage in any one of a series of notches 21 on the barrel whereby the spring can be raised or lowered for changing the range of the sighting device, there being a notch or peep sight 22 for use in connection with the front sight when shooting in the daytime. The rear end of the tube is adapted to be connected with the rear sighting device by a U-shaped clamping spring 23 detachably connected by a screw or equivalent means 24 to the spring 17.

It will thus be seen that by adjusting the spring, the light-projecting device can be set for any given range. When the light-projecting device is not to be used in connection with the gun, the spring 23 can be readily detached so as not to be in the way.

From the foregoing description, taken in connection with the accompanying drawing, the advantages of the construction and 10 of the method of operation will be readily apparent to those skilled in the art to which the invention appertains, and while I have described the principle of operation of the invention, together with the device which 15 I now consider to be the best embodiment thereof, I desire to have it understood that the device shown is merely illustrative, and that such changes may be made when desired as are within the scope of the claims 20 appended hereto.

Having thus described the invention, what I claim is:—

1. The combination of a rifle, a front sight therefor, an adjustable rear sight, a light-

projecting device, means for attaching the 25 front end of the device to the rifle, and means for attaching the rear end of the device to the rear sight for adjustment therewith.

2. The combination with the barrel of a 30 fire-arm, of a light projecting tube, a ring for holding the tube pivotally connected at one end to the barrel, a tube tilting member connected with the barrel and disposed at the opposite end of the tube from said ring, 35 means for changing the angle of the tilting member relatively to the barrel for varying the range, and a spring clasp connecting the tube with the tilting member for adjustment with the latter, the tube being detachable from said ring and clasp.

In testimony whereof I affix my signature in presence of two witnesses.

HIRAM A. FOSS.
